United States Patent Office

Des. 195,277
Patented May 21, 1963

195,277

COIN DISPENSING MACHINE OR SIMILAR ARTICLE

Otis E. Hoffman, Watertown, Wis., assignor to Brandt
Automatic Cashier Company, Watertown, Wis., a cor-
poration of Wisconsin

Filed Dec. 4, 1961, Ser. No. 67,790

Term of patent 14 years

(Cl. D52—4)

FIG.1 is a view in perspective of a coin dispensing machine showing my new design and illustrating the front and left side of the machine; and

FIG. 2 is a view in perspective of the coin dispensing machine taken from a diametrically opposed position from the view of FIG. 1 and illustrating the rear and right side of the machine.

The dominant features of the design reside in the portions shown in full lines.

I claim:

The ornamental design for a coin dispensing machine or similar article, as shown and described.
